HERMANN ARNDT, OF BERLIN, GERMANY, ASSIGNOR TO SIEMENS & HALSKE, AKTIEN-
GESELLSCHAFT, OF SIEMENSSTADT, NEAR BERLIN, GERMANY, A CORPORATION
OF GERMANY.

AUTOMATIC BLOCK SIGNAL SYSTEM.

Application filed March 1, 1927; Serial No. 171,772, and in Germany February 22, 1926.

My invention relates to an automatic block signal system in which the various signals are given by means of roundels in spectacle castings in front of signal lamps.

5 One object of my invention is to provide means for controlling the signals by relays in dependence upon the state of the track sections.

10 A further object of my invention is to provide means of rendering the relays, apart from the state of the section, also dependent upon the state of the signal of the next block in advance.

15 A still further object of my invention is to provide means for protecting the block by the signal located in the rear, in the event of failure of one of the signals or when the signal lamps go out.

20 A still further object of my invention is to design the signal lamp in such a manner that the spectacles can be operated directly by the section relay appertaining to them.

25 In order to attain a dependence between the successive signals of the individual block sections the apparatus is according to my invention designed in such a manner that when the spectacles of any signal show red the auxiliary phase of the rear section relay receives current. If a signal behind the

30 train remains in the proceed position the advance signal is not given clear and thus protects the train. Only when the signal behind the train passes into the stop position and shows the red roundel does the auxiliary phase of the rear block relay receive current, thus attracting its armature and placing the green roundel in front of the respective lamp in the advance block. Preferably the arrangement should be such that when

35 the red roundel is shown the respective signal lamp or lamps are connected in series with the relay of the rear block. The arrangement must be such that the roundels are moved in dependence from the block relay,

40 so that when the relay has attracted its armature the green roundel of the spectacles appears in front of the signal lamp, but when the armature has dropped off and thus on short-circuit of one of the windings of the relay, the red roundel passes in front of the signal lamp. When the relay has responded i. e. when the green roundel is in working position, the line leading from the signal lamps to the auxiliary winding of the rear

55 relay is broken and the lamps must receive current over another line or ground. This may, for instance, be attained by providing in the block line a contact which interrupts the line between the signal lamps and the auxiliary winding when the armature of the relay has been attracted and simultaneously connects the lamps to ground, the contact being closed or opened either directly by the armature of the relay or of the spectacles. This dependence of the closing of the contact 60 from the spectacles themselves has the advantage that even when the armature of the relay has dropped off, but the spectacles are stuck for some reason an operation of the rear block relay is rendered impossible. Preferably the arrangement will be such that the spectacles 65 are operated by the armature of the relay. This may be attained in a particularly simple manner if elliptic reflectors are employed which require 70 a very small opening only for the passage of the rays and thus only small spectacle castings. Such elliptic reflectors are particularly adapted for the purpose because they 75 also permit of the provision of two sources 80 of light so that one serves always as stand-by source of light without the necessity of doubling the spectacle mechanism.

The drawings affixed hereto show diagrammatic representations of an embodiment of my invention by way of example.

In the drawings

Fig. 1 shows the state of an alternating current system when the train has entered the middle one of three blocks indicated, and

90 Fig. 2, the state of the system when the front portion of the train has reached the last of the block sections.

Like numerals of reference indicate like parts in both figures of the drawing.

95 Referring to Fig. 1, 1, 2 and 3 are three consecutive block sections. The train is just at the beginning of the block section 2. The block 2 is protected by the signal 4, the block 3 by the signal 5. Each of the signals consists of an elliptic reflector 6, 7 respectively and two respective sources of light 8, 9 and 10, 11 located in the foci of the reflector. In front of the openings of the reflectors which for the sake of clearness are shown in perspective view in the drawing, are located the spectacle castings 12, 13 with the red roundels or lenses 14, 15 respectively and the green roundels 16,

17 respectively. The spectacle castings are disposed to rock on pivot pins 18, 19 and are respectively coupled by a connecting rod 20, 21 with the respective armatures 22, 23 of the block relays 24 and 25. As pointed out before the spectacle castings can easily be operated by the relays since due to the small openings of the elliptic reflectors they may be made so small that very little power is required to operate them. In order to make the spectacles still more easily movable they are preferably so balanced that they are nearly in equilibrium in any position so that substantially only the necessary power for accelerating the masses need be supplied. The respective tail ends of the spectacles form contact levers 26, 27 which in one position when showing a green light, see spectacles 13, bridge over the stationary contacts 28 and 29, and when showing a red light, see spectacles 12, close the contacts 30. Each of the block relays 24 and 25 possesses two windings 31 and 32, one winding 31 receiving current across the rails of the block section 2 or 3 from the transformer 33, while the other winding 32 of each relay is connected in series with the lamps, or at least one of the lamps of the light signal ahead. For instance, in case of relay 24, its winding 32 is connected in series with lamp 10 of signal 5. This connection is made across the line 34 and the contacts 30 of signal 5. For the supply of current to the relays and the signal lamps two lines 35 and 36 are provided which may simultaneously feed the transformers 33. In order to attract its armature each relay must have both of its windings energized. The train is indicated by two axles 37 and 38. In this figure the train has just entered the block section 2 and has short-circuited the winding 31 of relay 24, the armature 22 of the relay has dropped off and has placed the spectacles 12 into the position in which the red roundel 14 appears in front of the opening of the reflector. In this position of the armature winding 32 of relay 24 is likewise deenergized, since now contacts 28, 29 are open, so that this winding cannot receive current from mains 35, 36 this way or receive current from these mains by way of line 34 aforementioned since contact 30 of signal 5 is then open. In this way the block section 2 is protected. The signal lamp 8 receives now current from the line 35 across line 39, the contacts 30 on the spectacles 12 and the auxiliary phase of the block relay in the rear, not illustrated. In the foregoing it is assumed that the block 3 is clear, the armature of the relay 25 has been attracted and the green roundel 17 is in front of the reflector of the signal 5. The lighting current flows here from line 35 across the line 40 and lamp 11 to the return line 36, or lamp 10, line 41, contacts 28 to the return line 36. Naturally the earth may equally well be used as return line.

Referring to Fig. 2 showing the state of the system after the train has entered the

block section 3, it will be observed that the front axle 38 of the train has short-circuited the winding 31 of the relay 25, so that the armature 23 of the relay has dropped off and the red roundel 15 has appeared in front of the opening of the reflector 5. So long as one of the rear axles 37 of the train is still within the block section 2 the winding 31 of the relay 24 remains dead and the armature 22 in the dropped off state. Only when all axles 75 of the train have left the block section 2 the winding 31 of the relay 24 receives current again. The relay can however attract its armature only when the winding 32 of the relay 24 also receives current. So long as 80 armature 22 of relay 24 has not been attracted, its winding 32 cannot receive current directly from mains 35, 36 by way of contact 29, then still open. This winding can, however, as aforementioned, receive current across the line 34 and the contacts 30 of signal 5 provided armature 23 of relay 25 has dropped off and the signal shows red light. Should the relay 25 stick or the supply of current to the signal lamp 10 fail, the winding 32 of the relay 24 would receive no current and the signal 4 would continue to show a red light and thus protect the block 3. Only after the armature 23 of the relay 25 has dropped off, as shown in Fig. 2 of the drawing, the winding 32 of the relay 24 receives current first along the following path: line 35, line 40, signal lamp 10, line 41, the contacts 30, line 34, winding 32, line 42 and return line 36. Relay 24 can now attract its armature and signal 4 will now show green light and clear block 2. As soon as the block 3 also becomes clear of the axles of the train, the armature 23 of the relay 25 is attracted again the connection through line 34 is interrupted and the winding 32 of relay 24 now receives current exclusively along its normal path: line 35, line 43, the contacts 29, line 44, winding 32, line 42 and the return line 36.

If one of the signal lamps, for instance lamp 9 or 11, as shown in the drawings, is directly connected to the current supply system, this has the advantage that when the contact controlled lamp, such as 8 or 10 has burned out or the contact 30 or 28 has failed, the block signal does not remain completely dark, but is illuminated by its directly connected lamp, such as 9 or 11.

Various modifications and changes may be made without departing from the spirit and the scope of the invention, and I desire, therefore, that only such limitations shall be placed thereon as are imposed by the prior art.

I claim as my invention:

1. In a block signal system, in combination a railroad track electrically divided into independent block sections, a signal lamp disposed at the entrance of each block and a

- spectacle device carrying a red and a green roundel, and being movably disposed to place either of said roundels before the lamp, a relay for each block having an armature for 5 operating the pertaining spectacle device, to clear or block its track section, said relay having a main energizing winding connected to the rails of that block to be short circuited by a train in that block, and an auxiliary winding, both windings being required jointly to energize the relay, means for supplying current 70 to the relays, signal lamps and to the rail section of each block, and means for connecting the auxiliary winding of the relay of the block signal about to be cleared in series with the signal lamp of the next block entered by 75 the train when the red roundel of that next block appears before its lamp, to complete the energization of said relay, so that even when the first-named block is cleared by the train, the signal clearance of that first block is 80 initiated by and rendered dependent from the correct blocking signal position of the newly occupied block.
- 10 4. In a block signal system, in combination a railroad track electrically divided into independent block sections, a signal lamp disposed at the entrance of each block and a spectacle device carrying a red and a green roundel, and being movably disposed to place either of said roundels before the lamp, a 85 relay for each block having an armature for operating the pertaining spectacle device, to clear or block its track section, said relay having a main energizing winding connected to the rails of that block to be short circuited by a train in that block, and an auxiliary winding, both windings being required jointly to energize the relay, means for supplying current to the relays, signal lamps and to the rail 90 section of each block, and a contact device operated by the signal spectacle of the next block entered, and line connections therefor for connecting the auxiliary winding of the block signal about to be cleared in series with the signal lamp of the newly entered block when 95 the signal spectacle of that block shows the red roundel, so that even when the first-named block is cleared by the train, the signal clearance of that first block is initiated by 100 and rendered dependent from the correct blocking signal position of the newly occupied block, and additional contacts operated by the spectacle of each relay when fully energized for connecting its own auxiliary winding directly to the current supply to 105 free the relay from the controlling influence of the block signal ahead.
- 15 5. In a block signal system, in combination a railroad track electrically divided into independent block sections, a signal lamp disposed at the entrance of each block and a spectacle device carrying a red and a green roundel, and being movably disposed to place either of said roundels before the lamp, a 110 relay for each block having an armature for operating the pertaining spectacle device, to clear or block its track section, said relay having a main energizing winding connected to the rails of that block to be short circuited by a train in that block, and an auxiliary 115 winding connected to the rails of that block to be short circuited by a train in that block, and an auxiliary 120 winding.
- 20 6. In a block signal system, in combination a railroad track electrically divided into independent block sections, a signal lamp disposed at the entrance of each block and a spectacle device carrying a red and a green roundel, and being movably disposed to place either of said roundels before the lamp, a 125 relay for each block having an armature for operating the pertaining spectacle device, to clear or block its track section, said relay having a main energizing winding connected to the rails of that block to be short circuited by a train in that block, and an auxiliary 130 winding.
- 25 7. In a block signal system, in combination a railroad track electrically divided into independent block sections, a signal lamp disposed at the entrance of each block and a spectacle device carrying a red and a green roundel, and being movably disposed to place either of said roundels before the lamp, a 90 relay for each block having an armature for operating the pertaining spectacle device, to clear or block its track section, said relay having a main energizing winding connected to the rails of that block to be short circuited by a train in that block, and an auxiliary winding, both windings being required jointly to energize the relay, means for supplying current to the relays, signal lamps and to the rail section of each block, and means for connecting the auxiliary winding of the relay of the block signal about to be cleared in series with the signal lamp of the next block entered by 95 the train when the red roundel of that next block appears before its lamp, to complete the energization of said relay, so that even when the first-named block is cleared by the train, the signal clearance of that first block is initiated by and rendered dependent from the correct blocking signal position of the newly occupied block.
- 30 8. In a block signal system, in combination a railroad track electrically divided into independent block sections, a signal lamp disposed at the entrance of each block and a spectacle device carrying a red and a green roundel, and being movably disposed to place either of said roundels before the lamp, a 100 relay for each block having an armature for operating the pertaining spectacle device, to clear or block its track section, said relay having a main energizing winding connected to the rails of that block to be short circuited by a train in that block, and an auxiliary winding, both windings being required jointly to energize the relay, means for supplying current to the relays, signal lamps and to the rail section of each block, and a contact device operated by the signal spectacle of the next block entered, and line connections therefor for connecting the auxiliary winding of the block signal about to be cleared in series with the signal lamp of the newly entered block when 105 the signal spectacle of that block shows the red roundel, so that even when the first-named block is cleared by the train, the signal clearance of that first block is initiated by and rendered dependent from the correct blocking signal position of the newly occupied block, and additional contacts operated by the spectacle of each relay when fully energized for connecting its own auxiliary winding directly to the current supply to 110 free the relay from the controlling influence of the block signal ahead.
- 35 9. In a block signal system, in combination a railroad track electrically divided into independent block sections, a signal lamp disposed at the entrance of each block and a spectacle device carrying a red and a green roundel, and being movably disposed to place either of said roundels before the lamp, a 115 relay for each block having an armature for operating the pertaining spectacle device, to clear or block its track section, said relay having a main energizing winding connected to the rails of that block to be short circuited by a train in that block, and an auxiliary winding connected to the rails of that block to be short circuited by a train in that block, and an auxiliary winding.
- 40 10. In a block signal system, in combination a railroad track electrically divided into independent block sections, a signal lamp disposed at the entrance of each block and a spectacle device carrying a red and a green roundel, and being movably disposed to place either of said roundels before the lamp, a 120 relay for each block having an armature for operating the pertaining spectacle device, to clear or block its track section, said relay having a main energizing winding connected to the rails of that block to be short circuited by a train in that block, and an auxiliary winding.
- 45 11. In a block signal system, in combination a railroad track electrically divided into independent block sections, a signal lamp disposed at the entrance of each block and a spectacle device carrying a red and a green roundel, and being movably disposed to place either of said roundels before the lamp, a 125 relay for each block having an armature for operating the pertaining spectacle device, to clear or block its track section, said relay having a main energizing winding connected to the rails of that block to be short circuited by a train in that block, and an auxiliary winding.
- 50 12. In a block signal system, in combination a railroad track electrically divided into independent block sections, a signal lamp disposed at the entrance of each block and a spectacle device carrying a red and a green roundel, and being movably disposed to place either of said roundels before the lamp, a 130 relay for each block having an armature for operating the pertaining spectacle device, to clear or block its track section, said relay having a main energizing winding connected to the rails of that block to be short circuited by a train in that block, and an auxiliary winding.

winding, both windings being required jointly to energize the relay, means for supplying current to the relays, signal lamps and to the rail section of each block, and a contact device operated by the signal spectacle of the next block entered, and line connections therefor for connecting the auxiliary winding of the block signal about to be cleared in series with the signal lamp of the newly entered block when the signal spectacle of that block shows the red roundel, so that even when the first-named block is cleared by the train the signal clearance of that first block is initiated by and rendered dependent from

the correct blocking signal position of the 15
newly occupied block, and additional contacts operated by the spectacle of each relay when fully energized for connecting its own auxiliary winding directly to the current supply to free the relay from the controlling influence of the block signal ahead, and further contacts also operated by the spectacle of each relay when fully energized for connecting its own signal lamp directly to the current supply. 20
